CYLINDER LOCK

Norman B. Hurd, Newington, Conn., assignor to
The American Hardware Corporation, New
Britain, Conn., a corporation of Connecticut

Application May 6, 1937, Serial No. 141,045

10 Claims. (Cl. 70—364)

This invention relates to improvements in cylinder locks and is primarily an improvement on the construction set forth in my former patent, No. 1,922,438, granted August 15, 1933.

5 My invention is particularly useful when employed with corridor locks having a fixed outer knob or one that may be dogged so that admission may be had only by the use of an appropriate key or keys. Briefly stated, my purpose 10 is to construct a cylinder lock in which one key is provided that is capable of operating the latch-bolt only, while a different key is provided that is capable of operating both the dead-bolt and the latch-bolt.

15 My main object is to accomplish the above end by a simple, durable and dependable construction, which I shall now set forth.

In the accompanying drawing—

Fig. 1 is a side elevation of the conventional door lock of the mortise type, the upper part of 20 the cap being removed to show a portion of the interior mechanism, and also showing the position that the cylinder lock occupies relatively thereto;

25 Fig. 2 is a relatively enlarged side elevation of the cylinder lock detached;

Fig. 3 is a cross-sectional view of Fig. 2 showing one position of the parts when one key is being used;

30 Fig. 4 is a similar view showing the position of said parts when a different key is used;

Fig. 5 is a side elevation showing the position of two different keys with relation to one of the elements that I will later term a "plug blocking" 35 device or tumbler.

1 represents a lock case, 2 the face-plate, 3 the spring latch-bolt, 4 the dead-bolt, and 5 the dead-bolt tumbler. 6 is a stud on the dead-bolt tail upon which is mounted a latch retracting 40 lever or member 7. 8 is a link pivoted at its upper end at 9, its lower end being slotted to stand over the stud 6. 10 is a lever pivoted at stud 11 on the side of the dead-bolt tail and engaging one arm of the latch-bolt retracting 45 lever to move the same and retract the latch-bolt. Part of the lever 10 is designed to be engaged by a key controlled roll-back 12 on the cylinder lock when the dead-bolt is retracted as shown in Fig. 1. By depressing this end of 50 lever 10, the latch-bolt 3 is retracted. When the dead-bolt is advanced, the lever 10 is similarly advanced to a position out of range of the roll-back 12 and hence cannot be operated thereby until the bolt has been again retracted.

55 Thus far I have described a well known form of

corridor mortise lock as typical of a lock with which my improved cylinder lock may be used to advantage.

Now, turning to the cylinder lock construction, 5 14 is the cylinder lock body, or cylinder, as it is sometimes termed. 15 is a rotatable key plug on the rear end of which is mounted the roll-back 12 or equivalent device. 16—16' represent the usual locking tumbler sections in the plug and cylinder respectively. 17 is a plug blocking 10 device or tumbler of substantial length, backed by a spring 17' and capable of reciprocal movement only in a passage in the cylinder body. This blocking tumbler is in approximately the same cross-sectional plane with the rearmost 15 locking tumbler 16' in the cylinder but is positioned at a different angle to the axis of the plug from that of said locking tumbler. A similar blocking tumbler 17'' is similarly located in the cylinder body on the opposite side of the 20 locking tumbler 16'. The end of each blocking tumbler is beveled off on the side toward the locking tumbler 16'. Means are provided to prevent either of said locking tumblers from rotating on their axes to thereby guarantee that the beveled ends will always face properly. In this case 25 both blocking tumblers and the passages in which they stand are of angular cross-section and hence the tumblers cannot turn. The plug 15 has the usual slotted keyway which cuts through the side 30 of the plug opposite the locking tumblers 16. When a key is inserted, the ends of the tumblers 16 stand flush with the outer cylindrical surface of the plug and the back of the key bridges that much of the keyway slot occupied 35 thereby so as to be flush with said cylindrical surface. 18 is a short key, the back of which stops short of the blocking tumbler 17, and consequently when the plug is turned counterclockwise to the position shown in Fig. 3, the blocking 40 tumbler 17 will be projected into the key slot and will check further rotation in that direction. If, however, the plug 15 should be turned in a clockwise direction as soon as the key slot reaches the blocking tumbler 17'' further turning 45 in that direction is stopped.

If a long key 19 is used, the back of said key will extend sufficiently far into the slot to bridge the same underneath the blocking tumblers 17—17'' and hence with such a key, the plug 15 50 may be turned freely in either direction to an unlimited extent.

Operation.—To illustrate how my improved cylinder lock functions, I have shown it as associated with a well known type of mortise lock 55

having a latch-bolt and a dead-bolt. Assuming the parts stand as indicated in Fig. 1 with the dead-bolt retracted. If the roll-back 12 is operated by a short key it may be turned in a counter-clockwise direction approximately to the position shown in Fig. 3, which is insufficient to depress the tumbler 5 and permit the dead-bolt to be projected. If the roll-back 12 is turned in a clockwise direction, it may move far enough to engage the lever 10 and depress it for the purpose of retracting the latch-bolt 3, but further movement will be prevented by the presence of the blocking tumbler 17" in the key slot. It will thus be seen that the function of the short key 18 is limited to retracting the latch-bolt only. If a long key 19 is used as shown in Fig. 4, it may be turned in a counter-clockwise direction to the position shown in Fig. 4 and beyond sufficiently far to depress the tumbler 5 and permit the roll-back to project the dead-bolt 4. When this rotation is completed, the roll-back will assume its normal position shown in Fig. 2 and the key may be withdrawn so that the door will be double locked with the latch-bolt 3 and dead-bolt 4. If the long key is again inserted, a clockwise rotation will cause the roll-back 12 to first pass the lever 10, then engage the tumbler 5 and withdraw the dead-bolt 4 so as to restore all parts to the position shown in Fig. 1. Now a partial turn to the right depresses lever 10 and retracts the latch-bolt.

In Figs. 3 and 4 I have indicated the blocking tumbler 17 as somewhat nearer to the locking tumbler 16' than is the blocking tumbler 17". This may be varied as occasion requires. In some instances, only one blocking tumbler may be employed to advantage. It will be observed that each blocking tumbler is of substantial length and thus has a relatively long and durable bearing that will offer sturdy checking resistance to the turning of the plug and which reduces any danger of jamming or functional failure of such parts.

While I have shown and described my invention in one preferred form, I appreciate that modifications may be made without departure from the spirit or scope of the invention as set forth in the following claims.

I claim:

50 1. In a cylinder lock, a cylinder body, a rotatable plug therein having a longitudinal key slot in one side, locking tumbler sections in said plug and body, a plug blocking tumbler supported in a passage in said body for reciprocal movement only, the end of said blocking tumbler being beveled off to be engaged by one edge of said key slot to be repressed thereby.

60 2. In a cylinder lock, a cylinder body, a rotatable plug therein having a longitudinal key slot in one side, locking tumbler sections in said plug and body, a plug blocking tumbler supported in a passage in said body for reciprocal movement only, the end of said blocking tumbler being beveled off to be engaged by one edge of said key slot to be repressed thereby, said blocking tumbler being located in substantially the same cross-sectional plane as the rear-most set of locking tumblers.

70 3. In a cylinder lock, a cylinder body, a rotatable plug therein having a longitudinal key slot in one side, locking tumbler sections in said plug and body, a plug blocking tumbler supported in a passage in said body for reciprocal movement only, the end of said blocking tumbler being beveled off to be engaged by one edge of

said key slot to be repressed thereby, said blocking tumbler being positioned at a different angle from the axis of the plug to that of the locking tumbler section in said cylinder body.

4. In a cylinder lock, a cylinder body, a rotatable plug therein having a longitudinal key slot in one side, locking tumbler sections in said plug and body, a plug blocking tumbler supported in a passage in said body for reciprocal movement only, the end of said blocking tumbler being beveled off to be engaged by one edge of said key slot to be repressed thereby, said blocking tumbler being positioned at a different angle from the axis of the plug to that of the locking tumbler section in said cylinder body, and a 15 second blocking tumbler in said cylinder body in the side opposite said locking tumbler section.

5. In a cylinder lock, a cylinder body, a rotatable plug therein having a longitudinal key slot in one side thereof, locking tumbler sections in said plug and body, a plug blocking tumbler mounted for reciprocation in a passage in said body, said blocking tumbler and passage being of angular cross-section to prevent the former from turning therein, the end of said blocking tumbler being beveled to be engaged by one edge of said keyway to be repressed thereby.

6. In a cylinder lock, a cylinder body, a plug rotatable therein having a longitudinal keyway in its side, key actuated locking means between 30 said plug and body, a plug blocking tumbler mounted in a passage in said body for reciprocal movement only toward and from said plug, the end of said blocking tumbler being beveled on one side only and toward the plug locking means, 35 for the purpose described.

7. In a cylinder lock, a cylinder body, a rotatable key plug mounted therein and having a longitudinal key slot in its side, a passage in said body radial to the axis of the key plug, a non- 40 rotatable blocking tumbler mounted in said opening for reciprocation only toward and from said plug, one side only of the end of said blocking tumbler being beveled, said bevel being located on the side toward the blocking tumbler, for the 45 purpose described.

8. In a cylinder lock, a cylinder body, a rotatable plug therein having a longitudinal key slot in one side, a passage in the cylinder body substantially radial to the axis of the plug, a 50 relatively long blocking tumbler mounted to reciprocate in said passage and supported by the walls thereof throughout a substantial portion of its length, the end of said blocking tumbler being beveled off at one side to form an inclined 55 surface to be engaged by said plug at one side of said key slot for repression of said blocking tumbler when said plug is rotated in one direction.

9. In a cylinder lock, a cylinder body, a plug 60 rotatable therein and having a longitudinal keyway, a locking tumbler, a blocking device in said body for abruptly engaging when projected the wall at one side of said keyway to check rotation of the plug in one direction, the end of said 65 blocking device being beveled off at the opposite side for engagement by the opposite wall of said keyway when said plug is rotated in the opposite direction to free said blocking device from said plug.

10. In a cylinder lock, a cylinder body, a plug rotatable therein and having a longitudinal keyway having an open back, a locking tumbler mounted in said body, a blocking tumbler mounted to reciprocate only in said body at one side of 75

said locking tumbler, the end of said blocking tumbler being beveled on the side toward the locking tumbler and having an abrupt shoulder at the opposite side, said shoulder being projectible into said keyway to block the limit of rotation of said plug in one direction and being displaceable from said keyway upon rotation of

said plug in an opposite direction, said blocking tumbler being displaceable and rendered ineffective by a proper key filling that part of the back of the keyway adjacent the end of said blocking tumbler.
